UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR CLEANING DEPHLEGMATORS

Original application filed October 18, 1923, Serial No. 669,251. Divided and this application filed April 13, 1925. Serial No. 22,559.

This application is a divisional of an application filed by me, Serial No. 669,251 filed October 18th, 1923.

This invention relates to a process for treating oils, and refers more particularly to the removal of solids or substantial solids from the interior of a dephlegmator, expansion chamber or still.

In the cracking of hydrocarbon oils, it has been found that retarding of the speed with which the vapors and oil flow, aids materially in the reaction of the material treated. One of the mechanical means now in use is a dephlegmator provided with a series of pans arranged one above the other in alternate fashion. In other words, the outer edge of the top pan will overlap the circular edge of the pan next below so that the overflow will fall from the top to the next, etc. This arrangement can be carried out throughout the height of the dephlegmator.

Heretofore, at the end of every few runs, it has been necessary to remove the top of the dephlegmator and take out the pans for cleaning and removing any carbon, sand, salt or other foreign solid or substantially solid materials.

I have discovered that after the run is completed, by the introduction of steam, benzol, or some such suitable solvent, these pans can be cleaned without removing them from the chamber. This is accomplished by positioning a vertical feed pipe in the chamber, which terminates just above the lowest pan. The opposite end of this pipe may be located outside and above the top and connected with the source of supply for the cleaning agent. Small discharge pipes of varying length to correspond with the position of the pans, are interposed in this vertical feed pipe just above each pan. The whole can be rotated to an angle of substantially 360° by means of a hand wheel attached to the vertical pipe.

Fig. 1 is a vertical cross sectional view of a dephlegmator equipped with my invention.

Fig. 2 is a cross sectional detail showing the arrangement of the vertical feed pipe and the outlets to the pans.

Referring in detail to the drawings, 1 des-

ignates a vertical dephlegmator for use in the cracking of hydrocarbon oils. This dephlegmator is of the usual type, having rounded top cap portion 2, which can be removed if necessary, and rounded bottom portion 3. The bottom portion 3 terminates in a reflux drawoff 4. The vapors are forced into the bottom of the dephlegmator, through the vapor inlet pipe 5. Raw oil may be introduced through the raw oil inlet pipe 6, and pressure distillate through the pipe 7, both of which may be used as temperature controlling or cooling mediums. Vapors may be drawn off through vapor outlet pipe 8. In the interior of the dephlegmator are positioned a plurality of small and large imperforate pans 9 and 10 of different diameters. The pans are held in place by vertical stay rods (not shown) in the usual manner.

Referring now to the feature of the invention, I provide a vertical feed pipe 11 extending substantially down the center of the dephlegmator, which may terminate just above the lowest pan, as shown at 12. The upper extremity of this vertical pipe 11 terminates in a swivel 13. The extension 14 beyond the swivel 13 is connected to the source of cleaning agent supply, such as steam, hydrocarbon distillate, benzol, etc. A valve 15 is interposed in the upper portion of the pipe for regulating the amount and pressure of the cleaning material.

Connected to the pipe 11 and located above each pan are a plurality of small outlet pipes 16 and 17 of varying lengths, which may be screw-threaded or welded into the pipe 11 as shown at 18 to facilitate their easy removal. The arrangement is such that a smaller pipe 16 will be directly above the pan 9 of smaller diameter while pipe 17 is long enough to bring its outlet over the pan 10. I may note here that the outer edges of the pans of smaller diameter overlap the inner circumference of the pans of larger diameter.

These outlet pipes 16 and 17 are adapted to be rotated through an angle of substantially 360° by means of the hand wheel 19. The stuffing gland 20 may be provided adjacent the hand wheel 19. It will be noted that the

vapor outlet 8 terminates in a T 21, upon which the base portion of the stuffing gland rests.

The operation is as follows: After a run 5 is completed, the dephlegmator is allowed to cool. Deposited on the pans there will be a certain amount of earthy matter, carbon and sludge. Steam in this instance, may be introduced under say 100 pounds pressure, 10 into the pipe 11, the valve 15 being open. The steam will be sprayed onto the surface of the pans through the outlet pipes 16 and 17, and the earthy matter deposited thereon quickly and easily removed. By rotating the 15 hand wheel 19 through an arc of slightly less than 360° and back again, the steam is forced onto the entire surface of the pans, thoroughly cleaning them and removing the foreign matter. If a gaseous or vaporous cleaning 20 agent is employed, the same may be removed through vapor outlet 8 or, if the valve therein has been closed, through outlet 4. The residual deposits will of course be removed through outlet 4 as will the liquid cleaning 25 agent, if such is employed.

I have illustrated my invention using steam as the cleaning agent, but it is obvious as pointed out, that other cleaning agents can be used.

30 I claim as my invention:

1. A process for removing solid and semi-solid residual-like accumulations from the vertically spaced pans of a dephlegmating column employed in the distillation of hydro- 35 carbon oil, consisting in discharging an independent stream of cleansing fluid under pressure into each separate pan, in changing the point of contact of said streams with said pans during operation, to thereby cause 40 said streams to contact with substantially the entire area of said pans, and in withdrawing the cleansing agent and removed residual deposits from the dephlegmating column.

2. A method for removing the residual accumulations of an oil cracking process from the vertically spaced baffling pans of a dephlegmating column used in an oil cracking process, consisting in discharging an independent stream of a cleansing fluid into 45 each pan in the dephlegmating column, in changing the point of contact of the streams of cleansing fluid with the pans during operation, to bring the cleansing fluid into contact with substantially the entire area of each 50 pan, to dissolve the residual accumulations in and flush the same from the pans, and in withdrawing the cleansing fluid and removed residual accumulations from the dephlegmating column.

55 3. A process for removing solid and semi-solid residual-like accumulations from the vertically spaced pans of a dephlegmating column employed in the distillation of the hydrocarbon oil, comprising discharging an independent stream of a cleansing fluid into

each separate pan under pressure, causing said streams to contact with each pan in the dephlegmating column, and withdrawing the cleansing fluid and removed residual deposits from the dephlegmating column.
